UNITED STATES PATENT OFFICE.

FRIEDRICH TREUDE, OF LADSPHE, GERMANY.

TIN SEAL.

1,067,081.

Specification of Letters Patent.

Patented July 8, 1913.

Application filed March 8, 1910. Serial No. 547,957.

To all whom it may concern:

Be it known that I, FRIEDRICH TREUDE, a subject of the German Empire, residing at Ladsphe i. Westphalia, Prussia, Germany, 5 have invented new and useful Improvements in Tin Seals; and I do hereby declare the following to be a full, clear, and exact description of the same.

The tin-seals used hitherto, whose halves 10 are united by connecting cross-pieces, showed, when they were put on, the drawback that owing to the length of the cross-piece, the point at which it had to be bent could not be exactly determined, so that 15 uniting the two halves by hand was almost impossible. This drawback is removed in the tin-seal forming the subject of this application by directly uniting, with the shortest possible bridge, the free edges of the 20 upstanding borders of the two halves of the seal, the connecting-cross piece being so short that a bending at any point can not take place, so that practically it can only be bent in one precisely determined point. 25 The shifting of the two halves of the seal out of their relative positions is thereby prevented, so that one half can be put into the other far more easily. Moreover both halves of the seal are according to the present in- 30 vention provided in the center with protuberances projecting into the interior, between which the cord of the seal is held fast, the protuberance of one half serving to receive the marks to be stamped into the seal, 35 while upon the other the cord is placed, and the same serves also as a counter-die when the seal is stamped, while the cord constitutes an elastic support for the counter-die during the stamping.

40 The drawing illustrates a form of construction of the tin-seal according to this invention.

Figures 1 and 2 show an inside view of the opened halves of the seal and a vertical 45 section; Figs. 3 and 4 illustrate the tin-seal with the halves united, before the borders are bent, in a side-view and top-view. Figs. 5 and 6 show the seal after the bending of the borders in a sectional and top-view.

50 Similar letters refer to similar parts throughout the several views.

The present seal consists of the halves 1, 2, of which the latter possesses the raised border-rim 5, to which the disk 1 is almost 55 directly connected, as the cross-piece serving to fasten this disk is so short that when

the seal is put on it cannot be bent in any place, but only one precisely determined bending-point is practically possible.

When putting on the seal the two cords 60 are placed into the half 2 of the seal provided with the raised border 5 in a manner that they pass out through the cuts 4, 4 (Figs. 2 and 3) made at opposite sides of the same, whereupon the covering-disk is 65 bent over in the direction of the arrow (Fig. 2), and, by means of a pair of pincers the rim 5 (Figs. 5 and 6) is turned over upon the covering disk.

In consequence of the fact that there is 70 only a very short cross-piece between the two halves 1, 2 of the seal, there is not only avoided a shifting of the same out of their relative positions when the half 1 is bent, but the seal is also of a perfectly circular 75 shape with a smooth border, without any projecting parts, so that no one can be injured when the object to which the seal is affixed is transported, and in order that the improper opening of the seal may be pre- 80 vented.

As will further be seen from the drawing, the two halves of the seal are provided with inwardly projecting protuberances 7, 7¹, between which the cords 6 remain 85 firmly secured after the raised rim 5 has been bent (Fig. 5).

When marks are stamped into the protuberance 7¹, which either takes place simultaneously with the bending of the border 90 or as a separate process, the protuberance 7 forms the counter-die and, at the same time, with the cord squeezed in between them an elastic support for the stamping-process.

What I claim as my invention and desire 95 to secure by United States Letters Patent is:

1. A sheet metal seal comprising a larger member having a wide upstanding border; a smaller member adapted to be received by said border and against and over which said border may be folded, said smaller member being directly joined to the free edge of the upstanding border of the larger member by the shortest possible bridge. 100

2. A sheet metal seal comprising two circular members one of which is adapted to be folded upon the other at its edges, each member being provided with an inwardly off-set middle portion; and a cord passing through the seal and clamped by and forming a cushion between the off-set portions. 110

3. A sheet metal seal comprising two cir-

cular members directly connected by the shortest possible bridge, one of said members having an upturned border provided with a diametrically opposite recess extending to the body part of the member, the other of said members being provided with a narrow upturned flange around which said border is adapted to be folded and held fast, the body parts of each of said members being provided with an inwardly off-set flat

middle portion, and cords passed and squeezed between said flat portions.

In testimony whereof, I have signed my name to this specification in the presence of two subscribing witnesses.

FRIEDRICH TREUDE.
